STOOL

John P. Salsgiver, West Acton, Mass., assignor to United Technical Corporation, Auburndale, Mass., a corporation of Massachusetts

Filed Nov. 19, 1968, Ser. No. 14,828

Term of patent 14 years

Int. Cl. D6—01

U.S. Cl. D15—8

Fig. 1.

Fig. 2.

FIGURE 1 is a plan view of the stool showing my new design; and

FIGURE 2 is a perspective view of the stool.

The side and end faces of the stool not shown in FIGURE 2 are the same in appearance as those shown.

I claim:

The ornamental design for a stool, as shown and described.
